Patented Sept. 17, 1957

181,003

PAPER CLAMP

Robert W. Greco, Brooklyn, N. Y.

Application September 4, 1956, Serial No. 42,823

Term of patent 3½ years

(Cl. D74—2)

Fig. 1

Fig. 2

Fig. 3

Fig. 1 is a top plan view of a paper clamp, showing my new design;

Fig. 2 is a front elevational view of the same; and

Fig. 3 is an end view of Fig. 2 looking from the right hand side thereof.

The essential features of my design reside in the parts shown in solid lines on the drawing.

I claim:

The ornamental design for a paper clamp substantially as shown and described.
